UNITED STATES PATENT OFFICE.

JULIUS BECKER, OF ESSEN-ON-THE-RUHR, GERMANY, ASSIGNOR TO FRIED. KRUPP AKTIENGESELLSCHAFT, OF ESSEN-ON-THE-RUHR, GERMANY.

GUN.

No. 886,576.

Specification of Letters Patent.

Patented May 5, 1908.

Application filed April 30, 1907. Serial No. 371,143.

To all whom it may concern:

Be it known that I, JULIUS BECKER, a subject of the Emperor of Germany, and a resident of 22 Hohenzollernstrasse, Essen-on-the-Ruhr, Germany, have invented certain new and useful Improvements in Guns, of which the following is a specification.

The present invention relates to guns having swing-mounts and the object of the invention is to provide guns of this type with a sighting device which has independent sighting line and which retains the adjusted direction at the target even in case the swing does not return completely to its firing position after firing.

In the accompanying drawings: Figure 1 is a side view of an embodiment of the invention with some parts assumed as broken away; Fig. 2 is a view corresponding to that shown in Fig. 1 but with positions of some of the parts changed; Fig. 3 shows a part of Fig. 2 on an enlarged scale and partly in section; and Fig. 4 is a section on line 4—4, Fig. 3, looking from above.

By means of horizontal trunnions, one of which (a') is shown in Fig. 4, the gun barrel A is in the known manner carried by a barrel carrier or swing B B' which is in the form of a two-armed lever. The carrier is swingingly mounted on a horizontal shaft D secured in the walls C C' of the mount. The arm B' of the barrel carrier has jointed connection with the piston rod e' of a fluid brake which has its cylinder E swingingly mounted in the walls of the mount and contains a recuperator spring (not shown in the drawings). The elevating mechanism is also of known construction and is provided with a toothed sector F which is turnable on the shaft D and has its arm f' connected with the gun barrel by means of a link F². The sector F meshes with a toothed wheel F³ which is mounted on a shaft F⁴ journaled in the walls C C' of the mount. The shaft F⁴ carries a worm wheel F⁵ which meshes with a worm F⁶ journaled in the wall C of the mount, the shaft of the worm being provided with a hand wheel F⁷. A turning mechanism of known construction serves to secure the horizontal adjustment or training.

One (a') of the two trunnions of the gun barrel is provided with a cylindrical extension a² (Fig. 4) having its axis coinciding with the axis of the trunnion. The extension a² forms the pivot for a bell crank lever G G'

which in the following will be referred to as the sight carrier. One end of a link H (Figs. 1 and 2) is pivotally connected to the arm G of the sight carrier. The other end of the link is jointed to a bearing c² which is arranged on the wall C of the mount. The arrangement and the dimensions of the parts are selected in such a manner that the barrel carrier arm B, the link H, the arm G of the sight carrier and the bearing c² with the wall C of the mount form a parallel link system. The arm G' of the sight carrier terminates in an arcuate track G² which is provided with a groove g³ curved concentrically with the axis of the horizontal trunnions.

An elevation segment K carrying on its lower end a sight telescope L is guided in the track G² by means of a rail k' engaging in the groove g³. The guide rail k' is provided with teeth k² which mesh with a worm gear g⁴ of known construction journaled in the track G². The elevation segment K carries a scale M on which can be adjusted a mark a⁴ (Fig. 3) of an indicator A³ which is rigidly connected to the extension a².

The mode of laying the gun is as follows: Let it be assumed that the parts are in the positions shown in Fig. 1, in which the sighting line and the axis of the bore of the barrel are horizontal, and the barrel carrier B B' is in its normal firing position. By means of the turning mechanism, the lateral direction or horizontal training is first adjusted and if necessary, viz. when the target is outside of the horizontal plane through the sighting line, the sighting line is directed at the target by means of the worm gear g⁴ k². Thereupon the gun barrel is elevated by turning the hand wheel F⁷, the indicator A³ partaking of the movement of the gun barrel. As soon as the mark a⁴ of the indicator A³ registers with the division line of the scale M corresponding to the distance of the target the necessary elevation has been imparted to the gun barrel. From the above explanations, it follows that the sighting device in the present case is one with so-called "independent sighting line." After the firing, the barrel-carrier B B' swings rearwardly overcoming the resistance of the fluid brake and the recuperator spring, and the carrier again swings forwardly under the action of the recuperator spring. On this movement of the barrel carrier, the arm G of the sight carrier is subjected to a parallel displacement which is also partaken of by the

105
110

sighting line which consequently remains parallel to its original position at any position of the barrel carrier. The sighting line will, therefore, point at the target with an accuracy that is completely sufficient in practice, also in case the barrel carrier does not swing entirely forward to its normal firing position but comes to rest a little prior to reaching this position so as to occupy, for instance, the angular position shown in Fig. 2. This is likely to occur in guns having swing-mounts. When a stationary target is fired at, and the sighting line has once been adjusted at the target, it is consequently not necessary to again take aim at the target; it suffices to adjust the mark a^4 of the indicator A³ to the division line of the scale M that corresponds to the range.

Having thus described the invention, what is claimed as new and desired to secure by Letters Patent is:

1. The combination with a swinging barrel carrier and the barrel carried thereby, of a sight carrier movably arranged on a part partaking of the swinging movement of the barrel carrier, a sighting device carried by the sight carrier, and means causing the sight line of the sighting device to be maintained parallel to its original position for any posi-

tion that the barrel carrier can assume in any one vertical plane.

2. The combination with the barrel and the mount, of a parallel link system comprising a swinging barrel carrier, a sight carrier movably mounted on a part partaking of the swinging movement of the barrel carrier, a part of the mount not partaking of the swinging movement of the barrel carrier and a link connected to this part and to the sight carrier.

3. The combination with the mount, a swinging barrel carrier; and the barrel carried thereby; of a sight carrier movably arranged on a part partaking of the swinging movement of the barrel carrier and comprising a double armed lever, an arcuate track carried by one arm, and an elevation segment adjustable on the track; a sighting device carried by the segment; an indicator fixed on the part carrying the sight carrier, and a link connecting the sight carrier and the mount.

The foregoing specification signed at Dusseldorf, Germany, this thirtieth day of March, 1907.

JULIUS BECKER.

In presence of—

M. ENGELS,
ALFRED POHLMAYER.
